UNITED STATES PATENT OFFICE.

WILLIAM F. SCHERER, OF WESTON, WYOMING.

RAILROAD-TIE.

1,315,042.

Specification of Letters Patent. Patented Sept. 2, 1919.

Application filed February 26, 1919. Serial No. 279,812.

To all whom it may concern:

Be it known that I, WILLIAM F. SCHERER, a citizen of the United States of America, residing at Weston, in the county of Campbell and State of Wyoming, have invented new and useful Improvements in Railroad-Ties, of which the following is a specification.

As its principal object, the invention seeks to provide a metallic railroad tie of hollow construction and semicircular conformation in cross section, so that the tie proper may act as a covering for a concrete supporting medium which it is intended shall be contained in the hollow portion.

A further object of the invention resides in the provision of unique and efficient rail attaching means whereby the rails are effectively secured to the tie by clamping members which do not have to be bolted thereto.

Still further and other objects appear hereinafter as the invention is set forth in detail.

As shown and described, a specific embodiment of the invention is adhered to but to this embodiment the invention is not to be restricted. The actual reduction to practice may suggest certain desirable changes or alterations and the right is reserved to make any which do not deviate from the scope of the annexed claims.

In the accompanying drawings:

Figure 1 is a top plan view of the improved tie showing the positions of the rails attached thereto.

Fig. 2 is a front elevational view of the structure shown in Fig. 1.

Fig. 3 is a section on the line 3—3 of Fig. 1.

Fig. 4 is a section on the line 4—4 of Fig. 1.

Fig. 5 is a transverse sectional view of the tie looking at the inside of the rail.

Fig. 6 is a perspective view of the detachable rail securing clamp.

Fig. 7 is a perspective view of the clamping dog.

As shown, the invention comprises a tie body 1 which is of hollow construction as shown and of semicircular conformation in cross section. On top of the tie and for a specified length from either end and on either side of the transverse center there are formed the V-shaped recesses 2, so that there is left a rib 3 of the shape of a trapezium in cross section, the top face of the tie being

formed flat to leave the upper or larger base of the trapezoidal conformation. At the inner end of the rib 3, the top face of the tie is undercut to leave the rail base engaging projection 4 and the base of the rail 5, on one side is overhung and engaged by this projection. The opposite side of the base of the rail 5 is overhung and engaged by the flange 6 of the clamping member 7, this member being of greater length than the width of the rib 3, so that the dove tail slot 8 may be formed in its under face, this dove tail slot providing means to permit the clamping member to be slidably engageable over the rib 3. But at its longitudinal center, and on the side opposite the flange 6, the clamping member has a recess 9 formed therein, this recess being for the reception of the nose 10 of the locking dog 11.

The rib 3 adjacent to the end of the tie is formed with a transverse dove tail slot 12 and the rib is further formed with a depression 13 adjacent the dove tail slot 12, this depression receiving the heel 14 of the locking dog, the tongue 15 of which rests in a second depression 16 formed in the bottom of the dove tail slot, so that the top of the tongue will lie flush with the bottom of the said slot.

This dove tail slot is designed to receive the V-shaped locking wedge 17, the bottom of which, when the wedge concerned, rests upon the tongue 15 and secures the locking dog in place, the nose of the locking dog engaging in the recess 9 of the clamping member 7 and thus serving to hold it in firm engagement with the rail 6. The locking dog and the wedge thus serve to secure the clamping member laterally while the rib 3 serves to secure the clamping member in such a way as to enable it to resist any force tending to raise the rail from the tie.

It is believed that the foregoing description clearly illustrates the manner of attaching the rails to the improved tie and in the use of the latter it is purposed to fill the hollow interior space with concrete, thus providing a tie capable of resisting all compressive strain.

The invention having been described what is claimed as new and useful is:

* 1. The combination with a tie having inverted trapezoidal shaped ribs formed on its upper face adjacent its ends, of clamping members slotted on their underface for slidably engagement with said ribs, the clamping

members and tie both having rail base engaging means, locking dogs, the clamping members having recesses formed therein to receive the noses of the locking dogs, the 5 aforesaid ribs having depressions formed therein to receive the heels of the locking dogs, the locking dogs being formed with tongues and the ribs having further depressions to receive the said tongues, and V- 10 shaped wedges carried in the dove tail slots the bottoms of which coincide with the tops of the depressions, whereby the wedges are adapted to lock in the tongues in said depressions.

15 2. The combination with a tie having in-

verted trapezoidal-shaped ribs formed on its upper face adjacent its ends, of clamping members slotted on their underface for slide- 20 able engagement with said ribs, the clamp- ing members and the tie both having rail base engaging means, locking dogs having one end engageable with the clamping mem- 25 bers, and V-shaped wedges insertable in slots formed transversely across the tie, the said wedges engaging the locking dogs to main- tain the latter in engagement with the clamping members.

In testimony whereof I affix my signature.

WILLIAM F. SCHERER.
